att,

UNITED STATES PATENT OFFICE.

MAX HAUSHEER, OF ST. OUEN, FRANCE.

BOOKKEEPING DEVICE.

Application filed August 10, 1925, Serial No. 49,345, and in Switzerland August 26, 1924.

The present invention relates to book-keeping devices according to the loose leaf and manifold writing system having a journal leaf and account leaves which carry columns for figures on their margins.

With such book-keeping devices the entries for debit and credit have to be made separately. The presence of mistakes in the balance amongst the entries can only be ascertained by a comparison of the additions of the debit and credit columns on the journal leaf or on a control sheet. The exact location of the mistakes, their number and kind can only be traced by comparing the entries point by point.

It is the object of the present invention to prevent such mistakes from occurring in consequence of an erroneously or carelessly made entry or to provide for a means of readily tracing such mistakes. With the arrangement according to the present invention each account leaf for every account is provided along at least one of its longitudinal margins with a row of apertures spaced a distance from each other equal to the line spacing and the rows of apertures of similar accounts being similarly arranged, but the rows of apertures of the credit accounts being so displaced relatively to the rows of apertures of the debit accounts that when the leaves are correctly placed one above the other for making an entry the row of apertures of the credit account sheet does not register with the row of apertures of the debit account sheet. Thereby it is rendered possible to apply two control marks in front of every entry in such a manner that one of said marks is made on the upper leaf and the second mark on the lower leaf, the second mark on the lower leaf being applied to the latter through the respective aperture of the upper leaf, which is not possible, if erroneously two leaves having similarly arranged rows of apertures such as for instance two credit account leaves or two debit account leaves have been placed one above the other for making an entry. The control marks entered with a correct entry facilitate further the tracing of the correct line on which the subsequent entry has to be made as the last control mark of the lower leaf must be seen through the aperture on the same line of the upper leaf. Further a wrong entry is immediately seen on the journal leaf as when two similar account leaves or only one account leaf is utilized one of the

control marks applied through the registering apertures of the two similar account leaves placed one above the other or through the aperture of the row of holes of a single account leaf is made on the journal leaf.

A constructional example of the subject matter of the present invention is illustrated on the accompanying drawings, in which:

Fig. 1 shows three leaves correctly placed one above the other and after an entry has been made,

Fig. 2 is a cross-section of the leaves arranged one above the other wherein the thickness of the leaves is exaggerated,

Figs. 3, 4 and 5 show the three leaves singly,

Fig. 6 shows an account leaf with debit and credit account,

Fig. 7 shows a detail modification, and

Fig. 8 shows in a diagrammatic manner electrically operated means controlled by the row of apertures in the account leaves for stopping the operation of a book-keeping machine when the leaves are wrongly placed above each other.

The leaves preferably of contrasting colors placed above each other in the manner illustrated in Fig. 1 may be held in their proper position by means of one of the many known clamping devices for loose leaf bookkeeping, which device is not illustrated on the accompanying drawings as it does not form part of the present invention.

The journal leaf 1, the colour of which may be red, is provided with columns for the text and one column for figures as is usual with bookkeeping arrangements of the aforementioned type, and with two lateral margins 1^a, 1^b ruled with thick lines. Two types of account leaves are provided, i. e. debit account leaves and credit account leaves. The debit account leaf 2 contains columns for the text and for the figures, which correspond to those on the journal leaf, as well as lateral margins 2^a, 2^b ruled with thick lines, the right hand margin 2^b being however somewhat smaller than the corresponding margin 1^b of the journal leaf 1. On each margin a vertical row of apertures is provided, the apertures 2^c of which are arranged between the horizontal lines and at the same distances from each other as the horizontal lines. While the debit account leaf 2 is for instance white, the credit account leaf 3 (Figs. 1 and 5) placed above the former may be of a light blue colour.

The credit account leaf 3 contains the same columns for the text and for the figures as the other two leaves and has lateral margins 3^a and 3^b ruled with thick lines. On each 5 margin a vertical row of apertures is provided, the apertures 3^c of which are arranged between the lines; these rows of apertures do not register with the rows of the leaf 2 as they are so arranged in the horizontal 10 direction that its apertures are beside the apertures of the leaf 2 and that the leaf 3 covers the apertures of the leaf 2. In front of each entry and on the same line as the former, two symbols, for instance asterisks 15 may be entered either by hand or by a machine, one of the symbols being set to the left of the aperture 3^c on the margin 3^a of the leaf 3 and the other being marked on the leaf 2 through the aperture 3^c of the leaf 3. 20 After the entry has been made on the same line of the latter a symbol *o* may be entered through the aperture 3^c of the margin 3^b on the margin 2^b of the leaf 2 and a further symbol to the right of the first symbol *p* on 25 the margin 3^b of the leaf 3 above the aperture 2^c of the leaf 2 which is particularly to be recommended with leaves having a great width for the sake of greater clearness.

The entry of an item, for instance of a 30 cheque received from the customer Messrs. Schuler & Cie., and endorsed to Schweiz. Volksbank for the amount of Frs. 20591.—is made in the following manner: On the journal leaf 1 a carbon sheet 4 is placed which ex- 35 tends in width exactly to the margins 1^a and 1^b so that the latter remain uncovered. On the top of the carbon sheet a debit account leaf 2 is placed so that the left hand vertical edges are flush, whereby the thick 40 ruling on the margins enables the lines to be brought into coincidence as the margin 2^b is slightly smaller than the margin 1^b. Thereupon a carbon-sheet 5 which does not cover the margins is placed upon the leaf 2 (the 45 carbon sheets are omitted in Fig. 1 for sake of clearness), and on the top of the carbon sheet 5 the credit account leaf 3 is placed, the last entry on which must be on the same line as the two symbols on the lower leaves. 50 On the line on which the entry has to be made the white colour of the leaf 2 must be seen through the aperture 3^c of the light blue leaf 3 as its aperture 2^c must be situated beside the aperture 3^c when the leaves 55 are in their correct position. Then the two symbols and the item are entered as well as the symbols *q*, whereupon the entry is finished. If now instead of a credit leaf and a debit leaf two similar account leaves have 60 been used this will be immediately seen as the two check apertures on the line on which the entry has to be made coincide to that through the aperture 3^c or 2^c respectively (in case two credit account leaves or two debit account leaves or only one of any of these

leaves have been used) the red colour of the journal leaf will be seen; if in spite of this the entries are made with the prescribed control symbols or marks one of the latter will be placed on the journal leaf through the 70 apertures of the account leaves and thereby show that the respective entry is placed on the wrong leaf; if however, the entry of the control symbols is omitted by inadvertence or purposely these symbols are missing on 75 the account leaves and the respective entry shows the irregularity. The danger that the entry of the symbols has been forgotten is reduced by the fact that the symbol is at the left hand side and every entry has therefore to start with writing the control symbols. The journal forms nothing further than a chronological survey of all the entries and provides for the above mentioned possibility 80 of effecting a control.

The account statement leaf illustrated in Fig. 6 and which shows a debit account in its upper half and a credit account in its lower half is provided on each margin of the upper half with a row of apertures and 90 on each margin of the lower half with a row of apertures whereby the rows of the upper half are laterally displaced with regard to the rows of the lower half.

It may be pointed out that it is known to 95 provide rows of apertures in account leaves, the apertures of the rows being distanced from each other by the same amount as the lines and which are engaged by pins of transport sprocket wheels or chains for the 100 purpose of shifting the leaves by the line spacing after each entry. These rows of apertures are therefore not identical with the rows according to the present invention.

The apertures, which are shown in Figs. 105 1-6 to have a circular shape may obviously be of any shape, for instance of square shape as is shown in Fig. 7. The rows of apertures may also be displaced in the vertical direction instead of in the lateral direction so that the apertures 3^d of the credit account leaves 3 may be seen to be intermediate of the apertures 2^d of the debit account leaves as will be seen in Fig. 7.

If the book-keeping entries are not made 115 by hand but by means of a typewriter the control symbols may also be entered. Further the possibility exists to automatically prevent a wrong entry. To this end, for instance with flat type writers a locking 120 device as is illustrated in Fig. 8 may be provided in which two metallic contact pins 6 displaceably mounted in an arm 7 of the type writer and influenced by a spring 8 bear on the two rows of apertures; the 125 journal leaf 1 is without the margin 1^a so that to the left of the journal leaf 1 the metallic base plate 9 of the type writer is not covered by the journal leaf. An electric circuit 10 connects the base plate 9 to a 130

battery 11 and leads from the battery by the wire 12 to the spring 8 and thereby to the contact pin 6. The wire 12 energizes an electromagnet 13 the pole piece 14 of 5 which is connected to a rod 15 leading to a locking arrangement of the tabulator or of the type levers of the type writer. When the proper leaves are clamped one above the other, the contact pins 6 are insulated 10 against the base plate 9 by the leaves. When wrong leaves are used the apertures of which register, at least one of the contact pins 6 passes through the apertures and contacts with the base plate 9 whereupon 15 the electromagnet 13 is energized and locks the type writer. An entry can therefore not be made until the proper leaves are used.

I claim:

1. In a bookkeeping system, in combination, journal leaves provided with horizontal lines, columns and lateral margins, and credit and debit account leaves ruled in the same manner as the journal leaves and provided with the same appropriately designated 20 columns and having lateral margins and rows of apertures provided on at least one of said margins, said apertures being spaced from each other by the same distance as the horizontal lines and the rows on similar account leaves being in vertical alignment while the rows of the credit account leaves are displaced relatively to the rows of the debit account leaves when these two leaves are placed upon each other in such 30 manner that the horizontal lines and columns coincide.

2. In a bookkeeping system, in combination, journal leaves provided with horizontal lines, columns and lateral margins, and credit 40 and debit account leaves ruled in the same manner as the journal leaves and provided with the same appropriately designated columns and having lateral margins and rows of apertures provided on at least one of said 45 margins, said apertures being spaced from each other by the same distance as the horizontal lines and the rows on similar account leaves being in vertical alignment while the rows of the credit account leaves are laterally displaced relatively to the rows of the debit 50 account leaves when these two leaves are placed upon each other to cause the lines and columns to coincide.

3. In a bookkeeping system, in combina-

tion, journal leaves provided with horizontal lines, columns and lateral margins, and credit and debit account leaves ruled in the same manner as the journal leaves and provided with the same appropriately designated columns and having lateral margins ruled with 55 thick lines and rows of apertures provided on at least one of said margins, said apertures being spaced from each other by the same distance as the horizontal lines and the rows on similar account leaves being in 60 vertical alignment whilst the rows of the credit account leaves are laterally displaced relatively to the rows of the debit account leaves when these two leaves are placed upon each other in a manner that the lines and 65 columns coincide.

4. In a bookkeeping system, in combination, journal leaves provided with horizontal lines, columns and lateral margins, and credit and debit account leaves ruled in the 70 same manner as the journal leaves and provided with the same appropriately designated columns and having lateral margins on both sides ruled with thick lines and the 75 margins on one side of the credit account sheets being of different width to that of the margins on the same side of the debit account sheets and rows of apertures provided on at least one of said margins, said apertures being spaced from each other by the 80 same distance as the lines and the rows on similar account leaves being in vertical alignment whilst the rows of the credit account leaves being laterally displaced relatively to the rows of the debit account leaves 85 when these two leaves are placed upon each other in a manner that the lines and columns coincide.

5. In a bookkeeping system, journal leaves having horizontal and vertical ruling 90 and debit and credit account leaves ruled in like manner and having lateral margins and vertical rows of apertures in at least one of the margins thereof, said apertures spaced in correspondance with the horizontal ruling, 95 the rows on similar leaves being in alignment and those of different leaves being laterally displaced, said leaves being of contrasting color and different widths.

In testimony whereof, I have signed my 100 name to this specification.

MAX HAUSHEER.
